PRIEST'S COLLAR

Stephen A. Snincak, Power, W. Va.

Application March 1, 1956, Serial No. 568,762

4 Claims. (Cl. 2—129)

This invention generally relates to an improved collar and more particularly relates to an improved detachable collar of that type which is worn by clergymen in connection with bosom or shirt fronts.

In this type of collar the shirt fronts are disposed on the inside of the collar in present day practice. This arrangement provides a space or gap between the neck of the wearer and the collar since the neckband portion of the shirt front is normally relatively thick. This space or gap between the neck of the wearer and the collar forms a very loose fitting collar and one which looks unkempt. Since the shirt front in the presently available collar construction is adjacent to the skin of the neck, irritation and discomfort to the skin is caused because of perspiration and movement of the neck. Therefore, the shirt front becomes easily soiled and these shirt fronts are extremely difficult to launder. Accordingly, it is the primary object of the present invention to provide an improved collar construction of multiple plies with the shirt front disposed between the lower edges of adjacent plies and wherein the upper and lower edges of the collar are provided with rolled edges or folded edges thereby eliminating the sharp edges of the collar and especially the sharp edges which occur at the back along the line of juncture when the presently available collar is joined.

A further object of the present invention is to provide a collar which is attached to the shirt front by improved snap fastener means rather than the collar buttons which protrude through the collars and will engage the surface of the neck of the wearer. Such collar buttons sometimes oxidize when perspiration comes into contact thereto which irritates and discolors the skin.

Yet another object of the present invention is to provide a collar having a snap fastener means at the rear thereof together with novel joint means for providing a relatively thin joint wherein no sharp edges are disposed in contact with the skin of the neck of the wearer.

Other objects of the present invention will reside in its simplicity of construction, ease of assembly, adaptation for its particular purposes and its relatively inexpensive manufacturing cost.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a perspective view of a collar of the present invention assembled on a shirt wherein the collar is completely visible from the exterior with the neckband of the shirt concealed;

Figure 2 is a perspective view of the collar construction of the present invention illustrating the joint at the rear of the collar;

Figure 3 is a detailed sectional view taken substantially upon a plane passing along section line 3—3 of Figure 1

2

illustrating the relationships of the elements of the collar wherein it is in assembled position;

Figure 4 is a detailed sectional view taken substantially upon a plane passing along section line 4—4 of Figure 1 illustrating the manner in which the collar is attached to the neckband of the shirt front;

Figure 5 is a perspective view of a modified form of collar construction wherein the neckband of the bosom or shirt front is disposed exteriorly of the collar and is generally black rather than white which is the color of the collar;

Figure 6 is a detailed sectional view taken substantially upon a plane passing along section line 6—6 of Figure 5 illustrating the joint construction and arrangement;

Figure 7 is a detailed sectional view taken substantially upon a plane passing along section line 7—7 of Figure 5 illustrating the manner of attaching the neckband of the shirt front to the exterior of the collar;

Figure 8 is a detailed elevational view illustrating the ends of the collar prior to their assembly in encircling relation to the neck of the wearer; and,

Figure 9 is a detailed side elevational view illustrating the relationship of the free ends of the collar when they are assembled.

Referring now specifically to the drawings, the numeral 10 generally designates the collar of the present invention which includes an elongated member of unitary construction having an inner portion and an outer portion 14 joined together along the upper edge thereof in a rolled edge 16 which generally forms a longitudinal fold line between the inner and outer portions 12 and 14. The inner portion 12 is provided with a reversely bent lower edge 18 forming a lower rolled edge 20 and the reversely bent lower edge portion 18 terminates above the lower edge of the outer portion 14 of the collar 10 and the entire construction is made of any suitable material such as plastic or the like which will be sufficiently stiff for the purposes intended and will retain its shape.

As illustrated in Figure 2, the collar 10 is provided with free ends 22 and 24 with the one free end 22 having the reversely bent portion omitted for a considerable length with the numeral 26 indicating the terminal end of the reversely bent portion 18. On the other end 24 of the collar 10 the upper rolled edge 16 is omitted for a length with the numeral 28 indicating the terminal end thereof.

The outer portion 14 adjacent the free end 24 terminates in a rounded tab 30 having an aperture therein designated by the numeral 32 and the rounded end 30 of the outer portion 14 is spaced from the free end 24 of the collar 10. Disposed on the outer surface of the inner portion 12 adjacent the free end 22 is a male portion of a snap fastener while a female portion 34 is provided on the outer portion 14. When the free ends 24 and 22 are interconnected, the inner portion 12 of the free end 22 is disposed against the inner surface of the inner portion 12 of the free end 24 and the aperture 32 is positioned in overlying relation to the male portion of the snap fastener and the female portion 34 of the snap fastener is then snapped into position thereby retaining the collar 10 in encircling relation to the neck of the wearer. In this condition, the free end 22 of the collar 10 abuts the terminal edge 28 of the upper rolled edge 16 and the free edge 24 of the reversely bent portion 18 abuts the terminal edge 26 adjacent the free edge 22 thereby forming a substantially continuous telescopedly engaged collar joint with only the rounded free edge 24 of the inner portion 12 disposed in contact with the skin of the neck and due to the rounded upper corner of the free edge 24 of the inner portion 12, this edge will not cause discomfort due to irritation since it is disposed at the back of the neck where very little movement of the neck occurs. The remainder of the

60

65

periphery of the collar 10 is provided with a rolled upper and lower edge with the rolled upper edge engaging the neck and eliminating considerable of the discomfort caused by the usual sharp edges of a stiff collar.

A shirt front or bosom 36 is provided with a reinforced upstanding neckband 38 which is provided with a snap fastener element for engagement with a snap fastener element 42 disposed on the outer surface of the reversely bent portion 18 of the collar 10. This permits the collar 10 to be disposed against the skin of the wearer thereby eliminating any space between the collar 10 and the neck and also provides a rolled edge for the collar 10 and also disposes the entire area of the outer portion 14 for providing a continuous white collar.

Referring now specifically to Figures 5-7, it will be seen that an identical construction in the collar is illustrated and the same reference numerals are employed in conjunction therewith. In this particular instance, a different type of shirt front or bosom 36' is employed and which is constructed of some type of material which is generally black. The shirt front or bosom 36' is provided with an upstanding reinforced neckband 38' which is provided with snap fastener elements 49' for engagement with snap fastener elements 42' which are attached to the outer surface of the outer portion 14' of the shirt collar 10'. In this particular instance, it is noted that the outer portion 14' extends completely to and terminates at the lower rolled edge 29' wherein the neckband 38' will be disposed exteriorly of the collar 10' but the collar 10' will still engage the neck of the wearer in closely spaced relation and present rolled upper and lower edges 16' and 28' for engagement by the neck during twisting or nodding of the head thereby reducing irritation to the neck. Also, the snap fastener arrangement is so constructed that none of the fastening elements are disposed interiorly of the collar and the collar 10 or 10' prevents a continuously smooth surface except for the free edge 24 and 24', respectively, which substantially reduces the irritation to a minimum.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the inventions as claimed.

What is claimed as new is as follows:

1. A detachable collar for use by clergymen and attachment to a shirt having an upstanding neckband, said collar comprising an elongated member having free overlapping ends, said elongated member having inner and outer portions joined at their upper edges and forming a rolled upper edge for the collar, said inner portion having an outwardly extending reversely bent lower edge forming a lower rolled edge for the collar, said outer portion of the collar terminating in a lower edge overlapping the free edge of the reversely bent lower edge of the inner portion of the collar, the free ends of the outer portion of said collar adapted to receive fastening means for securing the collar in encircling relation to the neck of

the wearer, and means on said collar for detachable engagement with the shirt neckband, one free end of the collar having a length of the reversely bent lower edge of the inner portion omitted, the other free end of the collar having a length of the rolled upper edge omitted whereby the inner portion of said one free end overlies the inner surface of the inner portion of said other free end with the outer portion of the one free end underlying the outer portion of the other free end of the collar thereby forming a substantially flat telescopic joint.

2. The combination of claim 1 wherein the outer portion of the collar is provided with snap fastener elements adjacent the lower edge thereof for engagement with matching snap fastener elements on the inner surface of the neckband of the shirt whereby the neckband of the shirt will overlie the outer portion of the collar.

3. The combination of claim 1 wherein the reversely bent lower edge of the inner portion of the collar is provided with a snap fastener element for engagement with a matching snap fastener element on the inner surface of the neckband of the shirt whereby the outer portion of the collar will overlie the neckband.

4. A detachable collar for use by clergymen and attachment to a shirt having an upstanding neckband, said collar comprising an elongated member having free overlapping ends, said elongated member having inner and outer portions joined at their upper edges and forming a rolled upper edge for the collar, said inner portion having an outwardly extending reversely bent lower edge forming a lower rolled edge for the collar, said outer portion of the collar terminating in a lower edge overlapping the free edge of the reversely bent lower edge of the inner portion of the collar, the free ends of the outer portion of said collar adapted to receive fastening means for securing the collar in encircling relation to the neck of the wearer, and means on said collar for detachable engagement with the shirt neckband, one free end of the collar having a length of the reversely bent lower edge of the inner portion omitted, the other free end of the collar having a length of the rolled upper edge omitted whereby the inner portion of said one free end overlies the inner surface of the inner portion of said other free end with the outer portion of the one free end underlying the outer portion of the other free end of the collar thereby forming a substantially flat telescopic joint.

5. The combination of claim 4 wherein the outer portion of the collar is provided with snap fastener elements adjacent the lower edge thereof for engagement with matching snap fastener elements on the inner surface of the neckband of the shirt whereby the neckband of the shirt will overlie the outer portion of the collar.
